UNITED STATES PATENT OFFICE

LOUIS G. BEERS, OF TRENTON, NEW JERSEY, ASSIGNOR TO THE NEW JERSEY WIRE CLOTH COMPANY, OF TRENTON, NEW JERSEY, A CORPORATION OF NEW JERSEY

WIRE-CLOTH MEASURING AND DELIVERY TABLE

Application filed March 18, 1926. Serial No. 95,563.

The object of the present invention is to provide an improved wire cloth measuring and delivery table, by which any required lengths of the wire cloth may be readily and conveniently measured off and packaged for delivery, thus avoiding the inconvenience and liability to error resulting from previous methods of handling wire cloth for delivery.

10 For a full understanding of the invention, a detailed description of a construction embodying the invention in its preferred form will now be given, in connection with the accompanying drawings forming a part of 15 this specification, and the features forming the invention then specifically pointed out in the claim.

In the drawings—

20 Figure 1 is a plan view of the table, and Figure 2 is a side view, partly in section. Referring to the drawings, A is the table proper, supported at a suitable height and in any suitable manner, being shown as supported by posts or legs B. At one end of 25 the table a support C for a roll of wire cloth is provided, this support being shown as consisting of brackets secured on opposite sides of the table and carrying two rolls 1, 1 on which the wire cloth roll R is supported for rotation, and a guide roll 2. One of the rolls 1, 1 is provided with centering disks 3 at opposite ends between which disks the wire cloth is drawn off from the roll. On the rear side of the brackets is mounted 30 a cross-bar forming a brace 4, which forms a back-stop for the roll R so as to avoid all danger of the roll falling from the rear end of the table and to assure the proper position of the roll R without special care in placing it in position. At the opposite end 35 the table A is preferably provided with a suitable measuring machine D, which is shown as of a common type having rolls 5 for the support of a cloth roll, and counter 40 6 under which the cloth is drawn off, a wind-up roll 7 also being provided having a handle 8 by which the cloth may be wound up in any desired lengths.

Between roll support C and the measuring 50 machine D, the table is provided with a scale

a, shown as a foot scale running to six feet, and adjacent the roll support C with a more finely divided scale b, shown as an inch scale, so that any short lengths of material may be measured in feet and inches for packaging or delivery. On the underside of the table a slide 9 is preferably provided for an area card or other price or area calculating device, which may be withdrawn from its support and used on top of the table for calculation. The table also preferably carries on its underside a support 10 for a roll of wrapping paper 11, and a support 12 for a roll of sealing paper tape 13, gummed on one side for sealing the packages of wire cloth.

In operation the wire cloth roll R is placed on the rolls 1, 1 of roll support C and the wire cloth is drawn off under roll 2. If only short pieces of wire cloth are required, such cloth will be measured in the lengths required by the scales a, b, cut off on the measured line and wrapped or delivered. If a considerable length of wire cloth is required, the wire cloth is run over the table 75 under the counter 6 and onto the roll 7, where it is wound up to the length required as shown by the counter 6, either with or without the use of the scales a, b for exact determination of odd lengths. After the cloth has been wound up on roll 7, the counter 6 is swung back on its pivotal support, the roll 7 removed and the wire cloth thereon taken off for packaging on the table A. If it be desired to divide the wire cloth 80 roll R into rolls of shorter lengths measured by the counter 6, the wire cloth roll may be supported upon the rolls 5 and the table A not used, except for packaging the short length rolls successively removed from the roll 7.

What I claim is:

A wire cloth measuring and delivery table having at one end a support for a wire cloth roll during unrolling, a wire cloth measuring machine at a distance from the wire cloth support, said measuring machine having a support for a roll of wire cloth during unrolling and a roll for winding up the 100

measured cloth, and a scale on the table between the table roll support and measuring machine over which the unrolling wire cloth passes for measuring the wire cloth unrolling from the table roll support on the table.

5 In testimony whereof, I have hereunto set my hand.

LOUIS G. BEERS.
